UNITED STATES PATENT OFFICE.

CORYDON B. LAKIN, OF WASHINGTON, DISTRICT OF COLUMBIA.

CURTAIN-FIXTURE.

SPECIFICATION forming part of Letters Patent No. 716,060, dated December 16, 1902.

Application filed September 12, 1902. Serial No. 123,066. (No model.)

To all whom it may concern:

Be it known that I, CORYDON B. LAKIN, a citizen of the United States, residing at Washington, in the District of Columbia, have 5 made certain new and useful Improvements in Curtain-Fixtures, of which the following is a specification.

My invention is an improvement in curtain-fixtures, and has for an object, among others, 10 to provide a novel construction by which the curtain may be raised and lowered as usual, may be secured with its roller at the top of the window or at any lower point, and can be readily operated from one position to the 15 other in such manner as to permit light from the upper or lower portion of the window or from the upper and lower portion of the window; and the invention consists in certain novel constructions and combinations of 20 parts, as will be hereinafter described and claimed.

In the drawings, Figure 1 is an elevation of the upper portion of a window provided with my invention with the curtain and its roller secured in its uppermost position. Fig. 2 is 25 a similar view with the curtain-roller lowered in such manner as to freely admit light at the upper portion of the window. Fig. 3 is an elevation of the bracket shown at the left 30 in Fig. 1, the curtain-roller being in place. Fig. 4 is a similar view of the bracket shown at the right in Fig. 1. Fig. 5 is a detail perspective view of the bracket shown at the left in Fig. 1. Fig. 6 is a detail view, partly 35 in section, of the tension device for holding the operating-cords. Fig. 7 shows a somewhat-different construction of the bracket shown at the left in Fig. 1, and Fig. 8 is a diagrammatic view indicating the disposition 40 of the cords for supporting and operating the curtain-roller.

The curtain A and its roller B may be of ordinary construction, the latter being of what is known as the "Hartshorn" type, having 45 at one end the round stud C and the cord-pulley C' and at its other end the angular stud D and the cord-pulley D'. These pulleys C' and D' are fixed to the opposite ends of the roller B. The brackets E and F are 50 respectively at the left and right hand side of the window, (see Fig. 1,) corresponding to the studs D and C, and they are provided

with the downwardly-opening and flared seats e and f for the studs D and C, the seat e being angular at its upper end to hold the 55 stud D from turning and the seat f being rounded at its upper side to form a bearing in which the stud C can freely turn. The brackets E and F in the seats e and f correspond to the brackets ordinarily used with a 60 Hartshorn roller, with the difference that they open downwardly, so the curtain-roller can be moved upward into its seats e and f and will drop by gravity out of said seats, so the roller when up in the position shown in 65 Figs. 1, 3, and 4 can be operated after the fashion of an ordinary Hartshorn roller and yet can be freely lowered from such position to that shown in Fig. 2 when it is desired to admit light at the top of the window. It will be understood, therefore, that by constructing the brackets with the downwardly-opening seats e and f I am able to adjust the curtain-roller up to the position shown in Fig. 1, where it can be operated as 70 a Hartshorn roller, and at the same time can by the means presently described lower the curtain-roller to the position shown in Fig. 2 or to any other lower position desired and adjust the curtain to admit light and air at any 75 portion of the window-opening. The bracket E (shown at the left in Fig. 1) has its seat e provided at its upper end with the angular bearing e' for the square stud D of the roller B and opens freely downward from said bearing e', so the roller can readily adjust by gravity out of the seat e. It may be desirable to slightly swell the bracket-wing at e² adjacent to the seat e, as shown in Fig. 5, for the purpose of gaining some strength, and it 80 may be desirable to further swell the bracket adjacent to the seat, as shown at e³ in Fig. 7, when the bracket is formed, as shown in Fig. 7, to be secured against the inner face of the side of the window-frame, the construction 85 shown at e³ affording room for the stud D of the roller, as will be understood from the said Fig. 7.

The bracket E (shown in Fig. 5) is formed from a plate of metal with the wings E' and E², the latter being at a right angle to the wing E' and formed to be secured against the face of the window-frame, as shown in Figs. 1 and 2. At its outer edge the plate E' is

- provided with a projecting lug E^3 , which is bent at a right angle to the wing E' , and a similar lug E^4 is cut out of the wing E' , as shown at e^4 , and bent to a position parallel with the lug E^3 , the lugs E^3 and E^4 providing a bearing for the guide-pulley G for the cord, which supports the left-hand end of the curtain-roller, as will be understood from Figs. 1, 2, 3, and 5.
- 10 The bracket F has its seat f provided at its upper end with a rounded bearing f' for the round stud C of the curtain-roller B , and the said seat opens freely downward from the said bearing f' , so the roller B can move by gravity downward from its said bearing f' . This bracket F has lugs F' , through which may be passed the screws for securing it to the window-frame, and the guide-roller H is journaled in this bracket for the cords which support the right and left hand end of the roller B , as will be understood from Figs. 1, 2, and 8. Cords I and J are provided for supporting, respectively, the left and right hand ends of the roller B . The cord I is secured 25 at I' in connection with the window-frame at a point above the bearing e' . This connection may be effected through the bracket E' , which is provided at i' with a lug, to which the end I' of the cord may be fastened. The cord I extends thence down under the pulley D' of the roller B , thence up over the bracket-pulley G , thence across the window-frame over the pulley H , and thence down, where it is connected with the spring-tension device 30 K . (Shown in Figs. 2 and 6.) The cord J is secured at its upper end at J' in connection with the window-frame, (it may be to the lug j' on the bracket F , as shown in Fig. 4,) and extends thence downwardly under the roller-pulley C' , thence up over the guide-pulley H , and thence down to the tension device K , the depending lengths I^2 and J^2 of the cords being manipulated together in connection with the tension device K , so the said tension device 40 will exert a tension upon the cords J and K in such manner as to hold the same in any desired adjustment and so secure the curtain up in the bearings e' and f' or in any lower position to which the curtain may be adjusted.
- 45 This is an important feature of my invention—that is to say, the provision, in connection with brackets having downwardly-opening seats for the studs of the curtain-roller, of tension devices for holding the cords which 50 suspend the curtain so the curtain may be held by said cords through the aid of the tension devices up in the said bearings or down in any desired position.
- The tension devices, as shown in Fig. 6, include a casing L , which may be secured to the window-frame, a plunger M , and a spring N , by which the plunger is held normally downward or against upward movement. At its upper end the plunger M has a roller O , 55 grooved at its center O' and bearing above a plate or abutment O^2 the cords I and J , passing under the roller O and moving freely

when in the grooved portion O' of the roller, but capable of adjustment between the un-grooved end portions of the roller and the abutment O^2 , so the cords may be secured whenever desired. In clamping the cord between the roller O and the plate O^2 the cord may be drawn to one side of the groove O' in said roller, or, if desired, the ordinary clamping-roller having a cam-shaped groove commonly used in connection with curtain-cords may be used in place of the roller O , the specific construction of the said roller O taken alone forming no part of my invention. By this means the curtain may be raised to the position shown in Fig. 1 or lowered to the position shown in Fig. 2, and in either position will be held by the clamping of the cords I and J by the tension device K . At the same time when the roller is held up in the position shown in Fig. 1 the tension device K operates to hold the said roller in such position in a yielding manner, so the roller can turn in the bearing f' to permit the adjustment of the curtain up or down on the roller, as is usual with the Hartshorn fixtures.

In the operation of my curtain-fixture the curtain can first be adjusted to the position shown in Fig. 1, the shade then being pulled down to the bottom of the window or to any intermediate position, provided it may be desired to admit light and air at the lower portion of the window. Then by releasing the cords I and J from the clamping action of the tension device the said cords may be released and the roller lowered to the position shown in Fig. 2 or to any other lower position. In so doing the roller will turn in the cords I and J , so that as the roller B is lowered it will wind up the shade from above, so that the lower portion of the shade will not be disturbed from the position to which it has been adjusted. Then as the cords I and J are adjusted to raise the roller B they will turn the said roller, unwinding the top portion of the shade as the roller approaches the position shown in Fig. 1. To permit the cords I and J to wind up the shade with certainty, it is preferred to groove the curtain-rollers D' and C' , so that the cords I and J will fit tightly therein in such manner as to insure the turning of the roller by the operation of the cords, as before described.

It will be understood, especially from Figs. 5 and 7, that the guide-pulleys are grooved with V-shaped grooves, so the cord when properly fitted thereto will bind with sufficient force to insure the turning of the pulleys C' and D' by the action of the cords when the curtain-roller is lowered out of the brackets E and F . In this connection it will be understood, especially from Fig. 8, that the cords I and J do not pass entirely around the pulleys D' and C' , but only one-half around the said pulleys, so that when the roller B is adjusted up into its brackets, as shown in Fig. 1, the cords I and J will not prevent the turning of said pulleys with the roller in the

operation of the roller in connection with the ordinary Hartshorn spring and in the manner common to such spring, the yielding tension exerted longitudinally on the cords permitting the operation of the roller after the fashion of the ordinary Hartshorn roller when the parts are in the position shown in Fig. 1. It will also be understood that I provide pulleys at the opposite ends and fixed to the roller B, so that in the operation of the curtain from the position shown in Fig. 1 to that shown in Fig. 2, and vice versa, both ends of the roller are positively operated by the cords, as desired.

15 The construction is simple, easily applied and operated, possesses no parts likely to get out of order, and enables the curtain to be quickly adjusted to secure light and air at the upper portion of the window, at the lower portion of the window, or at both said portions, as may be desired by the user. It will be noticed the invention can be cheaply made and applied, involving no greater expense than the ordinary curtain-fixture.

25 Having thus described my invention, what I claim as new, and desire to secure by Letters Patent, is—

1. The improvement herein described, comprising the opposite brackets provided with 30 downwardly-opening seats for the roller-studs, one of said seats having an angular bearing for the angular stud, and the other a bearing for the round stud, and the seats opening freely below said bearings to permit 35 the curtain to drop by gravity therefrom, the curtain having its roller provided with the square and round studs and provided with pulleys grooved relatively to the curtain-cords, whereby the latter may fit tightly within 40 said grooves, and the curtain-cords and the guides therefor, the cords being disposed to provide depending portions looped a half-turn around the pulleys of the curtain-roller, and depending portions whereby they may be

manipulated, and the tension device exerting a longitudinal tension upon said cords, all substantially as and for the purposes set forth.

2. The combination in a curtain - fixture with a roller having studs, of the opposite 50 brackets having the downwardly-opening seats for the roller-studs, said seats having bearings for the roller - studs and opening freely downward from said bearings, whereby the roller may adjust by gravity out of the said 55 bearings of the seats, and means for supporting the curtain - roller and for holding same yieldingly in the seats of the brackets, substantially as set forth.

3. The combination substantially as herein 60 described, of the brackets having downwardly-opening seats for the curtain-roller and from which the said roller may freely drop by gravity, the cords for suspending the curtain-roller and by which it may be adjusted 65 into the seats of the brackets or permitted to drop out of said seats, guides for said cords, and tension devices exerting a longitudinal tension upon the said cords, substantially as set forth.

4. The combination in a curtain - fixture with the opposite brackets having downwardly-opening seats for the roller-studs, of the roller having end studs fitted to said seats grooved pulleys fixed to the roller at the opposite ends thereof, and the roller-supporting cords having depending looped portions fitting in the said grooved pulleys and also having depending manipulating portions, the tension device exerting a longitudinal ten- 75 80 sion on the said manipulating portions, and guide devices for the cords, substantially as set forth.
